FRITZ BRÜCK, OF OSNABRÜCK, GERMANY.

CONTROLLING APPARATUS FOR SUBMARINE MINES.

1,011,152.

Specification of Letters Patent. Patented Dec. 12, 1911.

Application filed July 5, 1910. Serial No. 570,268.

To all whom it may concern:

Be it known that I, FRITZ BRÜCK, engineer, subject of the King of Prussia, German Emperor, and residing at Osnabrück, Germany, have invented a new and useful Improvement in Controlling Apparatus for Submarine Mines, of which the following is a specification.

My invention relates to submarine mines 10 of the class intended to be deposited or planted by torpedo boats and other boats adapted to such use. Mines of this character are used for obstructing harbors, navi- gable streams and other water areas in times 15 of threatened or actual war.

My invention relates particularly to such mines of this class as are provided with an anchor adapted to rest upon or attach to the sea bottom and provided also with means 20 enabling them (more exactly their heads) to ascend from said anchor, when the mine, as a whole, is cast into the water or planted, until a predetermined depth below the surface of the water is attained, in which position 25 the mine proper is checked and fixedly held or clamped by a suitable device so that it cannot ascend higher. Mines of this kind are commonly provided with a light cable, windable upon a drum attached to the head 30 of the mine, terminating in a heavy weight or anchor. The head is so constructed as to be lighter than the volume of water which it displaces so that it will always tend to rise, from any depth to which it may have been 35 submerged, and float upon the surface of the water; by suitably determining the weight of the mine head the magnitude of the upwardly impelling force may be fixed as desired within wide limits.

40 To operate mines of the class above referred to, it is necessary to provide (1) that the mine as a whole (head and anchor) shall sink to the bottom before the head is released from said anchor, so as to rise there- 45 from; and while the mine is thus sinking the drum upon which is coiled the cord which unites head and anchor must be held immovable; (2) means which will prevent the head from ascending too rapidly through 50 the water, so that it may not have too great velocity at the moment when it has reached the predetermined depth at which it is to be permanently maintained, thus "overshoot- 55 ing" and unwinding too much cable; (3) means for clamping the cord and winding drum against further unwinding of said

drum and cord when the head has ascended to the proper distance from the surface of the water.

The means for checking the too rapid ascent of the head from the anchor has been described and claimed by me in an application for a United States patent filed December 8, 1909, Serial No. 532,104.

The preferred means used by me to actuate the clamping device by which the cord and drum is clamped when the head has ascended to its proper distance from the surface of the water, is a hydrostatic device which comprises, essentially, a box having 60 an opening closed by a hydrostatic plate; on the inside of this box is a compression spring which tends to force the plate away from the opening so as to release a second coiled spring which then unwinds and 65 throws the clamping devices into position to become effective. At the sea bottom the hydrostatic pressure of the water is sufficiently great to overpower this compression spring, keeping the plate pressed inwardly and preventing its actuating the clamp device proper through the second coiled spring referred to. As the head ascends, the hydrostatic pressure diminishes until, at the predetermined depth below the water surface, the compression spring is enabled to 70 push the plate outwardly, upon which the cord and winding drum are clamped and the head held fast. In using this hydrostatic device, it is obviously necessary to provide 75 some means by which the inward pressure upon the hydrostatic plate is maintained, and the compression spring prevented from acting, while the mine is descending from the deck of the boat from which it has been 80 cast and until the hydrostatic pressure itself becomes effective.

The object of my invention is to provide controlling means whereby it is possible at one and the same time by the operation of 85 a single device to rigidly unite head and anchor; to keep the hydrostatic plate pressed inwardly and the hydrostatic device as a whole, therefore, ineffective; and to clamp the winding drum and hold it immovable; until the mine (combined head and anchor) has reached the sea bottom, and to then simultaneously disconnect the head and anchor, release the winding drum, and allow the hydrostatic pressure to become the only 90 force working against the compression spring which controls the hydrostatic plate.

Referring to the drawings, Figure 1 is an elevation, part section, of a complete mine ready to be cast into the sea and embodying a preferred form of my control mechanism; Fig. 2 is a similar view, the upper part being broken away, of a modified form of my controlling mechanism; Fig. 3 is similar to Fig. 2, and embodies still another modification of my control mechanism; and Fig. 4 is a side elevation of the link used in Fig. 1 to connect the head and anchor.

In the drawings F is the mine head and G the anchor, the head being tapered and held in a frame P erected upon and attached to said anchor. Beneath the head is a winding drum Q suitably journaled in bearings attached to said head and having coiled upon it a cord D, the end of which is attached to the anchor G.

At the side of the winding drum, and provided with an arm pivoted to the drum support at B', is a sector B having, on its side away from the drum, an upwardly turned hook N provided with an oppositely extended arm N² which lies normally in a horizontal position at the bottom of the sector (Figs. 1, 2, and 3) and pivoted to the sector at N'; the arc of this sector carries a plug K and presses it inwardly, against the pressure of a circumferentially coiled spring M, so as to clamp drum Q. The hook N is held and prevented from rotating clockwise upon its pivot by means of a suitable soluble salt with which the space B² between the arc of the sector and the pivot N' is filled.

Attached to and below the winding drum is the hydrostatic box T at the opening of which is the hydrostatic plate C fixed to a central spindle U; a spring H within the box tends to push this plate outwardly.

Upon the anchor proper is fixed means adapted to bear against the extremity of the spindle U and keep the plate C positioned inwardly and spring H compressed until after the mine has reached the bottom. In Fig. 1 this means takes the form of an abutment V provided with an upwardly extended plane surface against which, when the head is in position, the spindle U will abut when at its extreme inward position. In this position, and when the connecting link A is also in place, it is obvious that the head F will be tightly held in and against the frame P. Spindle U may be pushed in to its extreme inward position and all the last bit of play between head F and support P be eliminated by screwing down nut W at the bottom of link A. Furthermore, owing to the inclination of the connecting link A, it is clear that any loosening between head F and anchor G which would permit of any increase in the distance between F and G, will result in pushing stem U still more forcibly against the abutment V, so that there is very little

risk of the hydrostatic device T being put out of adjustment and in operative position while the mine is in storage or upon the ship's deck before being cast into the water.

The upward turn of hook N together with the above referred to inclination of connecting link A makes it impossible for said link A to accidentally slip off said hook and sever the rigid connection of head and anchor.

In Fig. 2 everything is the same as in Fig. 1 except that, in place of the solid abutment V, there is placed a bell-crank lever V' having an upwardly extended arm 80 which abuts against the spindle U and a laterally extended arm upon which is adapted to rest a screw W' fixed at one end of a lever X the other end of which is attached to the bottom of the connecting link A. 85 By screwing W' down after the head has been placed in position and link A placed over hook N, all play of plate C upon the hydrostatic box T may be eliminated. The exact manner in which the sector B controls the plug K is in this form also somewhat different from the arrangement shown in Fig. 1. 90

Fig. 3 shows an arrangement of the controlling devices in which is combined the arrangement used for the sector B in Fig. 1 with the lever V' at the bottom of link A as employed in Fig. 2. 95

In operation, the mine as a whole, comprising head and anchor, as shown in Fig. 1 is thrown into the water from the ship's deck. Because of the greater weight of the anchor, the mine will sink in an upright position. After the anchor has reached the sea bottom, the soluble salt in space B² 100 which holds sector B in position is melted thus permitting the hook N to be rotated so as to free connecting link A and plug K. The head will immediately shoot upward and cord D unwind upon the drum Q. So 110 soon as the spindle U has passed the top of abutment V or V' as the case may be, the hydrostatic pressure will alone be effective to hold plate C in position, so that when the head has risen to its predetermined depth below the surface, the spring H is able to overpower said hydrostatic pressure and thus to actuate the plate C so as to operate the necessary clamp to check the drum and hold the cord D against further unwinding. 115

While I have described certain specific arrangements of controlling devices in this specification, I do not wish to be limited to the exact construction shown, but to be 125 able to vary details so long as they do not depart from the spirit of my invention which is embodied in the following claims.

I claim:

1. The combination, with a mine of the 130

class described provided with a head and an anchor as two elements; of a winding drum fixed to one of said elements; clamping means for said drum adapted to be released by the melting of a fuse and provided with a hook; a connecting link engaging said hook and joined to the remaining element; an abutment upon said last named element; and a hydrostatic box fixed to the winding drum and adapted to engage said abutment so as to be held in inoperative position; substantially as and for the purpose described.

2. The combination with a mine of the class described provided with a head and an anchor as two elements of a hydrostatic box for determining the length of the connecting cord between said elements; a releasable connecting link between said elements; an abutment adapted to engage the hydrostatic box and hold it normally inoperative; and means connected with said link for varying the pressure between said abutment and said hydrostatic box; substantially as and for the purpose described.

3. The combination, with a mine of the class described provided with a head and an anchor as two elements; of a winding drum fixed to one of said elements; clamping means for said drum; a link connecting the said two elements; and soluble fuse means for releasing said clamping means and for releasing said link.

4. The combination, with a mine of the class described provided with a head and an anchor as two elements; of a winding drum fixed to one of said elements; clamping means for said drum; connecting means in-

cluding a link for holding said two elements together; and a soluble fuse for simultaneously releasing the aforesaid clamping means and the aforesaid connecting means.

5. The combination with a mine of the class described provided with a head, an anchor, a cable connecting said head and said anchor, a winding drum for taking up said cable and a hydrostatic plate for clamping the winding drum and thus determining the free length of cable between said head and anchor, of means to simultaneously put the hydrostatic plate into inoperative position, lock the winding drum, and unite head and anchor independently of said cable, substantially as and for the purpose described.

6. The combination with a mine of the class described provided with a head, an anchor, a cable connecting said head and said anchor, a winding drum for taking up said cable and a hydrostatic plate for clamping the winding drum and thus determining the free length of cable between said head and anchor, of means including a link said means being adapted to simultaneously put the hydrostatic plate into inoperative position, lock the winding drum, and unite head and anchor independently of said cable, substantially as and for the purpose described.

In testimony whereof I have hereunto set my hand in the presence of two subscribing witnesses.

FRITZ BRÜCK.
